CONTAINER FOR CONVEYORS

BACKGROUND OF INVENTION

The present invention relates to containers for use in conveyor systems and particularly to a deformable receptacle for use in double-band conveyors.

Double-band conveyor systems are commonly employed to carry relatively lightweight material from place to place as, for example, in offices, libraries, schools, hospitals, research institutions, etc., where numerous documents must be continuously moved from floor to floor. In our copending application Ser. Nos. 17,242 and 17,476 filed respectively on Mar. 6, 1970 and Mar. 9, 1970, there is fully described such a system. Briefly such a system, the articles to be conveyed are held in a container, squeezed or clamped between the horizontal and vertical runs of a pair of parallel conveyor bands which are synchronously driven. The conveyor bands are pressed against each other by a series of opposed rollers to prevent the container from falling out, or being displaced relative thereto. A predetermined degree of pressure is obtained by the rollers which are spaced along the run of the belt and which also act to guide the direction of the movement of the conveyor. Difficulties are encountered, when rigid containers or containers of limited elasticity are used, since such containers cannot give under the pressure of the rollers, and tend to distort, break or bend causing damage to the contents therein. Such a problem arises, for example in the transport in hospitals of X-ray film which, while flexible, is particularly sensitive and fragile and cannot be bent beyond its flexible limit, folded or broken. An additional problem occurs when the container is required to turn a tight corner or one of small radius of curvature.

It is an object of the present invention to provide an improved container for use in double-banded conveyor systems.

It is another object of the present invention to provide a resilient and elastic receptacle for use in double-banded conveyor systems.

It is another object of the present invention to provide a container capable of holding sensitive and fragile articles.

It is still another object of the present invention to provide an improved double-banded conveyor system of the type described.

These and other objects as well as numerous advantages of the present invention will be seen from the following disclosure.

SUMMARY OF INVENTION

According to the present invention a container is provided comprising front and rear panels interconnected on three sides, along their peripheral edges, by sidewall members made of formed resilient material. The resilient material is covered by a flexible sheet having marginal flaps which are secured to the contiguous edges of the associated panels. In this manner a highly resilient, elastic and compressible receptacle is formed.

In the preferred form the sheet material is formed of fabric of either natural or synthetic material. The resilient material is preferably elastic having stretch characteristics. In one form the resilient walls are covered on only one face while in another form the wall is covered by the sheet material on both sides which form a pocket therefore.

The container can be made without a lid or cover but is preferably formed with one. In this case the lid is formed similarly as any of the other walls, with a resilient body and sheet covering; the sheet material however being secured only along one edge to a front or back panel to form a suitable hinge therefore.

Full details of the present invention are presented at length herein.

BRIEF DESCRIPTION OF DRAWING

In the following description reference is made to the accompanying drawing in which:

FIG. 1 is a perspective view of a container made in accordance with the present invention,

FIG. 2 is a vertical section through the container of FIG. 1, and

FIG. 3 is a horizontal section through one sidewall of the container of FIG. 1.

Turning now to the drawing there is shown a container, suitable for such purposes as receiving and holding a flexible but unbendable X-ray film F or the like. The container comprises a front panel 11 and a rear panel 12 both of rectangular configuration. The panels 11 and 12 are arranged in parallel planes with each other and are interconnected by a rectangular box like frame made of resilient sidewall members 13. The top wall of the receptacle is formed as a cover member, having a skirt 15 which is hinged to provide an opening 16 into the interior of the container. The front and rear panels are connected to the resilient sidewalls forming the side-bottom, and top walls by a flexible sheet covering 18 in the form of a strip or ribbon, preferably of fabric attached to either the front end or rear surfaces of the panels as hereafter described.

The front and rear panels 11 and 12 are formed of pliable but unbendable material, such as composition paper, heavy craft paper or flexible sheet plastic, while the wall members 13 are preferably made of unitary rectangular blocks, bands or sheets of soft foam rubber, or plastic which is elastic and yieldable under compression, twisting and shear stress. The term fabric when applied to the flexible cover 18 is intended to encompass, by definition, strips, ribbons or bands of woven or knitted textiles of natural or synthetic fibers or monofilamentary thread or yarn; or molded or cast sheets of synthetic material such as plastic. The cover 18 is required to be flexible but need not be elastic.

In one form, as seen in FIGS. 1 and 3, the sidewalls forming the vertical sides and the bottom of the container are covered only on their outer surfaces by the flexible sheets or strips 18 which have marginal flaps that extend beyond the edges of the respective wall portion. The extending flaps are permanently adhered to the outer surfaces of the contiguous edges of the front and rear panels 11 and 12. Synthetic glues such as epoxy resins or animal glues, etc., are suitable for this purpose. Preferably the flexible strips are also glued to the surfaces of the walls 13 as well as to the edges of the panels 11 and 12. The flexible sheet strips may be secured by other means such as stitching, stapling or heat sealing depending on the materials used.

In a second form, seen in FIG. 2, the interior surface of the respective vertical side- and bottom walls are also covered with the flexible fabric material. In this case, the resilient sidewalls are pocketed within the flexible strips so that completely covers and surrounds the surfaces of the wall portion. The fabric cover forms a lining on the interior surfaces which is protective of the elastic material of the wall member and also of the contents inserted in the container. As seen in FIG. 2 the inner flexible strips also have marginal flaps which may be secured to the flaps of the outer overstrips, before the two are jointly secured to the edges of the front and rear panel, or they may be secured to the panel's edges separately and on the inner face of the panel.

In either of the two forms shown, the fabric cover strips extend the length or breadth of the panels edges and are adhered securely to the edges of both the panel and the associated sidewall members. Thus, the flexible strips and the elastic sidewalls cooperate to provide a resilient flexible hinge connection between the sidewalls and the front and rear panels. The sheet foam, resilient and sponge material is capable of maintaining the container normally extended (i.e., open) to receive and hold the contents securely without crushing, but are sufficiently elastic that when placed between the rollers of the conveyor the container will give and yield without the need to bend the container or its content.

The cover member which forms the top of the container to give access to the opening 16, is constructed in a similar manner to that of the side- and bottom walls shown in FIG. 2, in that the elastic top wall member 13 is covered on both sides or pocketed between strips of flexible fabric 18. The fabric here however, has its extending marginal flaps secured to the

rear panel 12 only which as seen in FIGS. 1 and 2 permits the assembly to hingedly swing into closed and open position. Preferably, the marginal flaps extending from the rear are secured separately to both the front and back surfaces of the rear panel 12 to provide a strengthened hinge. The front marginal flaps used to cover the top wall are secured to the skirt member 15 which is designed to fall flat against the front panel 11. The skirt 15 and the front panel 11 are provided with cooperating adhesive strips 19, or other closing means which are adapted to maintain the skirt closed during use as seen in FIG. 2. If desired the skirt 15 may be omitted and the marginal edges of the textile strips extended and enlarged so as to act as a covering flap member.

It will then be obvious, that the present construction has the decided advantage of being readily compressible, stretchable and resilient in all directions, so that it is unimportant in which direction the container is held between the belts of the conveyor band. The container will yield elastically in all directions and the pressing of the container between the rollers of the conveyors, will not cause either the receptacle or its contents to be damaged or bent. Elasticity is limited by the textile material, and the compressibility and stretch characteristics of the wall material. Consequently the container can not be permanently compressed or bent. Even a folded X-ray film seen in FIG. 2 can be transported without damage.

Various changes and modifications can be made to the structure and form without departing from the concept of the present invention. Numerous variations have already been described, others will be obvious to those skilled in this art. It is therefore intended that the present disclosure be illustrative only and not limiting of the scope of the invention at all.

The embodiments of the invention in which an exclusive property or privilege is claimed are defined as follows:

1. A container for a conveyor system comprising front and

rear panels and at least three associated sidewalls interconnecting the same about their peripheral edges, said sidewalls being formed of resilient material and a strip of flexible sheet material covering the outer face thereof, said sheet material having marginal flaps secured along the peripheral edges of the outer faces of the associated panels to form a deformable rectangular receptacle.

2. The container according to claim 1 wherein said marginal flaps extend along the entire periphery of the panels and the corners thereof.

3. The container according to claim 2 including a second strip of flexible sheet material covering the inner face of said walls, said second strip having marginal flaps secured to said contiguous peripheral edges of said panels.

4. The container according to claim 3 wherein the marginal flaps of said sheet strips on the outer and inner faces of said walls are secured together to form a pocket for said wall.

5. The container according to claim 1 including a fourth sidewall having the marginal flaps of only one edge secured to one of said panels to provide a cover member for said receptacle.

6. The container according to claim 5 wherein said cover member comprises a rectangular wall of resilient material covered on each of its faces with a strip of flexible sheet material, the marginal flaps along three of the peripheral edges being secured together to enclose said wall in a pocket, the marginal flaps along the remaining edge being respectively secured to the front and back to form a hinge therewith.

7. The container according to claim 1 wherein said panels are of limited flexible sheet material is of limited elasticity.

8. The container according to claim 1 wherein said flexible sheet is formed of fabric material.
